UNITED STATES PATENT OFFICE.

WILLIS R. KING, OF NEWARK, NEW JERSEY, ASSIGNOR TO THE HANSON & VAN WINKLE COMPANY, A CORPORATION OF NEW JERSEY.

BASKET RAISING AND LOWERING DEVICE FOR ELECTROPLATING APPARATUS.

No. 882,783.

Specification of Letters Patent. Patented March 24, 1908.

Application filed September 13, 1906. Serial No. 334,405.

To all whom it may concern:

Be it known that I, WILLIS R. KING, a citizen of the United States, residing at Newark, in the county of Essex and State of New Jersey, have invented certain new and useful Improvements in Basket Raising and Lowering Devices for Electroplating Apparatus; and I do hereby declare the following to be a full, clear, and exact description of the invention, such as will enable others skilled in the art to which it appertains to make and use the same, reference being had to the accompanying drawings, and to letters of reference marked thereon, which 15 form a part of this specification.

The present invention has reference, generally, to improvements in apparatus for the electro-deposition of metals; and, this invention relates more particularly to a novel 20 means for raising and lowering the rotatable drum, cylinder, or basket, usually termed the "container", in which the articles which are to be plated are placed, from the tank.

The invention has for its principal object 25 to provide a novel raising and lowering mechanism for electro-plating apparatus provided with the usual rotatable basket or container and a shaft, both being removable from the tank, all with a view of more readily facilitating the removal of the basket or container 30 from the tank for the placing of the articles which are to be plated within the basket, and then just as easily and quickly lowering the basket or container down into the solution in 35 said tank.

Another object of this invention is to provide a novel means for readily retaining the basket or container in its raised position above the tank and in a position which enables 40 the workman to get at the basket with the least inconvenience for placing the articles in the basket or container or for removing the same therefrom.

Other objects of this invention not at this 45 time more particularly specified will be clearly understood from the following detailed description of the same.

My present invention consists, primarily, in the novel electro-plating apparatus and a 50 raising and lowering mechanism or device hereinafter set forth, for readily raising and lowering the basket or container, without interfering with the mechanism for coupling the driving shaft with the shaft of the basket or container, when within the tank of the

apparatus; and, furthermore, this invention consists in the various arrangements and combination of the devices and parts, as well as in the details of the construction of the same, all of which will be more fully described in the accompanying specification and then finally embodied in the clauses of the claims which are appended to and which form an essential part of this specification.

The invention is clearly illustrated in the accompanying drawings, in which:

Figure 1 is a plan or top view of an electro-plating apparatus and basket or container provided with a raising and lowering device embodying the principles of the present invention; and Fig. 2 is a front elevation of the parts represented in said Fig. 1. Fig. 3 is a view of the apparatus showing the end of the tank broken away, and illustrating also the basket or container and the raising and lowering mechanism in end elevation when in their lowered position within the tank; and Fig. 4 is a similar view of a portion of the tank, and the basket or container and the raising and lowering mechanism, these parts 75 being represented in their raised positions. Fig. 5 is a view of a portion of the opposite end of the tank and side view of a pivoted counterbalance connected with the raising and lowering mechanism; and Fig. 6 is a perspective view of a portion of the basket-supporting frame.

Similar characters of reference are employed in all of the above described views, to indicate corresponding parts.

Referring now to the said figures of the drawings, the reference-character 1 indicates a suitable plating tank or vat in which is placed the electro-plating solution. The said tank is preferably of the form and construction of my former patent No. 772,102, issued October 11th, 1904, and is provided at its opposite ends with the supporting bars 2 and 3, upon which is to be supported, in a manner to be presently more fully described, 100 a basket or container 4, the same being of any suitable construction. Extending outwardly from each end-member of the basket or container 4 are a pair of bearing-journals 5, through which extends a main shaft 6, for said basket or container, substantially in the manner of the construction illustrated in said Patent No. 772,102. The reference character 7 indicates a short spindle rotatively arranged in a suitable bearing 8 in one 105 110

end of the tank or vat, said spindle being operated by means of pulleys 9 and 10, and having a clutch-portion 11 adapted to be operatively connected with the member 12 of the main shaft 6, substantially in the manner of said Patent No. 772, 102. The said basket or container is suspended in its operative position within the tank or vat by means of a suspension frame comprising a 10 center bar 13, having a cross-rod 14 at each end, and each cross-rod 14 being provided with downwardly extending arms 15 which are formed with the inwardly extending extensions 16 terminating in and being secured at their lower ends to a bearing 17. The bearings 17 of the two side-frames, thus formed, are arranged upon the previously mentioned main shaft 6, substantially as shown. The said arms 15 are provided with 20 hook-shaped or other suitably formed supporting elements 18 and 19, and 20 is a tie or connecting rod arranged between the said elements 18 and 19, at each end of the basket or container. Each tie or connecting rod 20 is provided with an outwardly extending stud or journal 21.

When the basket or container and its suspension frame have by means of said hook-shaped elements 18 and 19 been arranged 30 upon the supporting bars 2 and 3, in the manner shown more particularly in Figs. 1 and 3 of the drawings, to suspend the basket or container within the body of the tank or vat, the flattened member 11 of the main 35 shaft 6 can be connected with the clutch-portion 10 so as to be operatively connected with the spindle 7; and, when the latter is operated from either of the pulleys or wheels 9 and 10 the container or basket will be 40 caused to revolve between the bearings 17 of the suspension frame.

Suitably secured at or near the upper edge of the front of the tank or vat are bearings 22 in which is adapted to oscillate a rod or shaft 45 23. Curved or other suitably formed arms 24 are secured by means of the parts 25 upon said shaft or rod 23, each arm 24 being provided at its opposite end with an eye 26 which is fitted over a stud or journal 21. A 50 lever or arm 27 is suitably secured in any desired position upon said rod or shaft 23, which, when moved in the direction of the arrow x in said Fig. 3, raises the supporting frame from within the tank or vat, so as to 55 lift the basket or container from its position within the tank or vat, shown in Fig. 3, to its position above and preferably at the front of the tank or vat, as indicated in Fig. 4 of the drawings. Suitably arranged and secured upon said rod or shaft 23, preferably 60 upon its opposite end, is a fixture 28, with which is connected a rod 29 which carries a weight or counter-balance 30, so arranged that it will facilitate the rising movement of 65 the basket or container, and parts, when the

lever 27 is moved forwardly and downwardly from the position shown in Fig. 3 to that indicated in said Fig. 4.

To retain the basket or container in its raised position above the tank or vat, for removing the plated articles or for adding another supply of articles, a finger or extension 31 has been secured upon said rod or shaft 23, at such an angle that when it engages a plate 32 upon the front of the tank or vat, the basket or container will have its central longitudinal plane moved beyond the central longitudinal plane of the rod or shaft 23, so that the tendency of movement of the basket or container will still be forwardly and downwardly. Such movement is however prevented by the contact of the finger or extension 31 with the plate 32, whereby the basket or container is safely retained in its raised position, as will be clearly evident.

As will be seen from an inspection more particularly of Figs. 1, 2 and 5 of the drawings, the previously mentioned fixture 28 is made with a shoulder or projection 33, and the weighted rod 29 is pivoted to said fixture 28 upon a pin or bolt 34, the said rod thereby being arranged that under normal conditions it will rest against said projection 33, as indicated. When, however, the basket or container has been lowered into the tank or vat, and that the said rod 29 and its weight may not provide an unnecessary obstruction upon the front of the tank, it can be folded down, as indicated in the dotted outline in said Fig. 5, with the weight resting upon the edge of the tank or upon a block 35 suitably secured upon the said edge.

I claim:—

1. In an apparatus of the kind described, a tank provided with an open top, bearings secured at the upper front portion of said tank, a shaft mounted in said bearings, a lever secured to said shaft for oscillating the same, arms secured to and extending from said shaft, said arms being provided at their free end-positions with bearings, a suspension-frame provided with journals mounted in said bearings, and a dipping basket or container rotatably mounted in said suspension frame, all arranged so that the oscillatory movements of said shaft will radially swing said arms and produce a rapid swinging movement of the dipping basket or container from within the tank to a point above and substantially in front of the tank, or vice versa, from in front of the tank to within the tank, substantially as and for the purposes set forth.

2. In an apparatus of the kind described, a tank provided with an open top, bearings secured at the upper front portion of said tank, a shaft mounted in said bearings, a lever secured to said shaft for oscillating the same, arms secured to and extending from said shaft, said arms being provided at their

free end-portions with bearings, a suspension-frame provided with journals mounted in said bearings, and a dipping basket or container rotatably mounted in said suspension-frame, all arranged so that the oscillatory movements of said shaft will radially swing said arms and produce a rapid swinging movement of the dipping basket or container from within the tank to a point above and substantially in front of the tank, or vice versa, from in front of the tank to within the tank, a rod extending from said shaft, and a counterweight on said rod, substantially as and for the purposes set forth.

3. In an apparatus of the kind described, a tank provided with an open top, bearings secured at the upper front portion of said tank, a shaft mounted in said bearings, a lever secured to said shaft for oscillating the same, arms secured to and extending from said shaft, said arms being provided at their free end-portions with bearings, a suspension-frame provided with journals mounted in said bearings, and a dipping basket or container rotatably mounted in said suspension-frame, all arranged so that the oscillatory movements of said shaft will radially swing said arms and produce a rapid swinging movement of the dipping basket or container from within the tank to a point above and substantially in front of the tank, or vice versa, from in front of the tank to within the tank, a rod extending from said shaft, and a counterweight on said rod, substantially as and for the purposes set forth.

20 4. In an apparatus of the kind described, a tank provided with an open top, bearings secured at the upper front portion of said tank, a shaft mounted in said bearings, a lever secured to said shaft for oscillating the same, arms secured to and extending from said shaft, said arms being provided at their free end-portions with bearings, a suspension-frame provided with journals mounted in said bearings, and a dipping basket or container rotatably mounted in said suspension-frame, all arranged so that the oscillatory movements of said shaft will radially swing said arms and produce a rapid swinging movement of the dipping basket or container from within the tank to a point above and substantially in front of the tank, or vice versa, from in front of the tank to within the tank, a rod extending from said shaft, and a counterweight on said rod, substantially as and for the purposes set forth.

25 5. In an apparatus of the kind described, a tank provided with an open top, bearings secured at the upper front portion of said tank, a shaft mounted in said bearings, a lever secured to said shaft for oscillating the same, arms secured to and extending from said shaft, said arms being provided at their free end-portions with bearings, a suspension-frame provided with journals mounted in said bearings, and a dipping basket or container rotatably mounted in said suspension-frame, all arranged so that the oscillatory movements of said shaft will radially swing said arms and produce a rapid swinging movement of the dipping basket or container from within the tank to a point above and substantially in front of the tank, or vice versa, from in front of the tank to within the tank, a rod extending from said shaft, and a counterweight on said rod, substantially as and for the purposes set forth.

30 6. In an apparatus of the kind described, a tank provided with an open top, bearings secured at the upper front portion of said tank, a shaft mounted in said bearings, a lever secured to said shaft for oscillating the same, arms secured to and extending from said shaft, said arms being provided at their free end-portions with bearings, a suspension-frame provided with journals mounted in said bearings, and a dipping basket or container rotatably mounted in said suspension-frame, all arranged so that the oscillatory movements of said shaft will radially swing said arms and produce a rapid swinging movement of the dipping basket or container from within the tank to a point above and substantially in front of the tank, or vice versa, from in front of the tank to within the tank, and means connected with said shaft for retaining the suspension frame and the dipping basket or container in their

raised positions above the tank, substantially as and for the purposes set forth.

4. In an apparatus of the kind described, a tank, provided with an open top, bearings secured at the upper front portion of said tank, a shaft mounted in said bearings, a lever secured to said shaft for oscillating the same, arms secured to and extending from said shaft, said arms being provided at their free end-portions with bearings, a suspension-frame provided with journals mounted in said bearings, and a dipping basket or container rotatably mounted in said suspension-frame, all arranged so that the oscillatory movements of said shaft will radially swing said arms and produce a rapid swinging movement of the dipping basket or container from within the tank to a point above and substantially in front of the tank, or vice versa, from in front of the tank to within the tank, a rod extending from said shaft, and a counterweight on said rod, substantially as and for the purposes set forth.

In testimony, that I claim the invention set forth above I have hereunto set my hand this 6th day of September, 1906.

WILLIS R. KING.
